UNITED STATES PATENT OFFICE.

EDWARD A. MELLINGER, OF CHICAGO, ILLINOIS, ASSIGNOR, BY MESNE ASSIGNMENTS,
TO AUTOMATIC ELECTRIC INC., OF CHICAGO, ILLINOIS, A CORPORATION OF DELA-
WARE.

AUTOMATIC TELEPHONE-EXCHANGE SYSTEM.

Application filed January 28, 1908. Serial No. 413,044.

My invention relates to automatic or semi-automatic telephone exchange systems in which the exchange apparatus is controlled by the subscribers or other persons over metallic lines which have no operating grounds at the substations thereof, systems of this kind being commonly known as two-wire systems, inasmuch as the operation of the exchange apparatus is not dependent upon a third conductor.

Generally stated the object of my invention is to provide an improved and highly efficient two-wire system of the automatic trunking type.

Special objects are to provide a two-wire system having no special high resistance coils at the substations thereof; to provide a two-wire system in which the selectors and connectors are each provided with only one double-wound line relay, instead of with a pair of line relays as heretofore; to provide an arrangement by which the trunk-release is more efficient than heretofore, the back-release relays of the selectors being connected in multiple or parallel between the battery and the trunk-release conductors, whereby the trunk-release circuit extending back from the connector includes the said back-release relays in parallel; to provide a subscriber's individual preliminary trunking switch that will automatically release and restore itself if placed or left off normal when the subscriber's line is in normal condition; to provide an improved arrangement whereby the trunks extending between the subscribers' line switches and the first-selectors are each composed of only two parallel conductors; and to provide certain details and combinations and features of improvement tending to increase the general efficiency and serviceability of a two-wire automatic or semi-automatic telephone exchange trunking system.

To the foregoing and other useful ends, my invention consists in matters hereinafter set forth and claimed.

In the accompanying drawings Figure 1 illustrates one of the subscribers stations A and a portion of the exchange apparatus, in a system embodying the principles of my invention.

Fig. 2 shows another one of the substa-

ers' stations A' and a still further portion of the exchange apparatus.

Figs. 1 and 2 taken together illustrate an established connection between the subscribers A and A', the subscriber A being the calling subscriber.

Fig. 3 is an enlarged view of the master switch and of the subscriber's individual switch, in which latter his line terminates. The line switches are divided into groups, and to each group there is allotted one master switch.

Fig. 4 is the preferred arrangement of the master switch bank.

Fig. 5 is a detail view of the preferred construction of impulse-transmitting apparatus at the telephone.

Fig. 6 shows the terminal apparatus of the trunk-line leading from one level of the banks of the second-selector switch H, which terminal apparatus may be located in a manual board, or in any suitable place.

As shown in these drawings, only one battery B, preferably grounded at G, supplies the exchange with all necessary current for talking and operating purposes, but in actual practice this arrangement may be modified and a number of such batteries may be provided and arranged in any suitable manner—that is, one battery may be used for operating one section of the exchange and another battery for operating another section, or a plurality of batteries may be made to operate in multiple or in series. Obviously, any combination of batteries may be employed, depending upon the conditions to be met.

As shown, the line of the substation A terminates in the line switch C. This line switch is shown more in detail at C in Fig. 3. The master switch that controls the selective operations of this line switch, and of all other line switches of the same group, is shown at D in Figs. 1 and 3. The line switch C is a trunking switch and is provided with a plurality of bank jacks which are assembled to form one line switch bank (not shown). Each of these bank jacks E is the terminal of the trunk-line which terminates (as shown in this case) in a first-selector switch F. It will be understood, of course, that these bank jacks E are multiple jacks—that is, all of the line switches of

the same group are provided with similar jacks connected to the same trunk-line. It will also be understood that when one line switch is occupying one of these jacks no other line switch can come in on the same trunk-line. The first-selector F is also a trunking switch, and is provided with sets of bank terminals each of which sets terminates in a second selector switch H. Exactly as the line switch bank jacks are multiple jacks, so the first-selector bank terminals are multiple terminals. The first-selector switches, following the general arrangement of a system in which automatic trunking switches are arranged on the percentage basis, are arranged in groups, and each switch of a group is, of course, provided with a multiple contact for each trunk-line, so that all of the first-selectors of the group to which the first-selector F belongs have access to the same second-selectors. In a similar manner the second-selector H is provided with multiple bank terminals to which are connected trunk-lines that terminate in connectors, one of which latter is shown at I. Of course, the line switch C allotted to the substation A' is the same as the line switch C. In order that this system may be more easily understood, the various mechanisms will first be described in detail as to their mechanical features, and after this is done the circuits will be carefully pointed out by describing the process by which one subscriber calls another subscriber. The subscriber's station apparatus is of the general type which is now in use in such places as Grand Rapids, Mich., Los Angeles, Calif., etc., but is improved upon in certain respects, mainly to adapt it to the telephone system herein disclosed. As shown, this substation comprises the usual receiver 2, transmitter 3, induction-coil 4, ringer 5, switch-hook 6 and impulse wheel 7. The said impulse wheel 7 is mounted upon the shaft 8 which extends through the telephone, and said shaft is provided with a dial (not shown) which is mounted on the end behind the impulse wheel (considering the phone shown in Fig. 1). Said dial is provided with the usual finger holes suitably marked with numerals or letters to guide the subscriber in making a call. Associated with this dial there is also the usual finger stop (not shown) to determine the limit of the downward movement of the dial each time that it is rotated in accordance with some digit. The impulse wheel is provided on its periphery with a set of suitable impulse teeth 9 which are twisted out of the plane of the impulse wheel for the purpose of obliquely engaging the lug 10 on the impulse spring 11, whereby the said spring 11 may be separated from the spring 12 a proper number of times

as the impulse wheel 7 returns to its normal position. It will be understood, of course, that in connection with this impulse wheel there is provided a suitable clock-spring (not shown) which is adapted to be wound up each time the subscriber pulls down the dial, and which constitutes the means for returning the impulse wheel to its normal position each time. It will also be understood that a suitable stop (not shown) is provided to limit the return movement of said impulse wheel. Of course, the induction-coil 4 is provided with primary and secondary windings 13 and 14, respectively. As this is a common battery system the transmitter 3 in series with the primary winding 13 are bridged across the line conductors when the subscribers are talking. The receiver 2 is in a closed local circuit, in series with the secondary winding 14. The switch-hook 6 is not only used for holding the receiver 2, as is ordinarily the case, but is also adapted for switching the spring 15 back and forth between the springs 16 and 17, so that when the receiver is on the switch-hook—that is, when the switch-hook is down—the springs 15 and 17 are maintained in contact for the purpose of bridging the ringer 5 in series with the condenser 18 across the line; but when the receiver is off the switch-hook—that is, when the switch-hook is up—the springs 15 and 16 are brought into contact for the purpose of closing the talking circuit. Although the arrangement of the springs shown at substation A (Fig. 1) may be employed, a preferred arrangement of the springs is shown in Fig. 5. The spring 11 is not directly operated by the impulse wheel 7, but in place thereof an extra spring 11^a is provided which is equipped with the lug 10 and is directly engaged by the impulse wheel 7, so that on the return motion of the impulse wheel the spring 11 is separated from the spring 12 by the action of the spring 11^a, preferably through an insulating member 11^b.

The line switch C, which is allotted exclusively to a subscriber (see Fig. 3), is a simple mechanism comprising the so-called trip magnet 19, the release magnet 20 and the bridge-cut-off relay 21. These magnets may be mounted on any suitable frame. Of course, said magnets should be properly mounted and raised far enough from the frame to insure the proper operation of their armatures, springs and other details which these armatures control. As shown, the cut-off relay 21 is provided with cut-off relay springs 22, 23, 24 and 25. These springs are so arranged that normally the springs 22 and 23 are in contact and the springs 24 and 25 are also in contact. Furthermore, when the magnet 21 operatively energizes, the said springs are separated as shown. The release

magnet 20 must also be raised sufficiently to permit the operation of an armature 26 suitably pivoted at a point 27. This armature is, of course, provided with a retracting spring 28 which normally retains the said armature 26 against the stop 29. As indicated, this armature carries at its forward end, and pivotally mounted thereon, the arm 30 of the trip magnet 19. Also mounted on the same frame, and in about the position shown relative to the trip and release magnets 19 and 20, is the so-called plunger arm 31 which is pivotally secured to the frame by the pin 32. This arm is provided on the side nearest the release magnet 20 with a spring 33 permanently secured to said arm 31 at or about its right extremity. As indicated, this spring extends to the left over the point 32—that is, between the point 32 and the release magnet 20. The left end of this spring 33 is free from the arm 31, and is received by a link 34 which is hung to a suitable member 35 secured to the forward end of the arm 30, as shown. It will be seen, therefore, that owing to the link 34 the spring 33 is retained under tension and tends to rotate the arm 31 about the pivot 32 in a clockwise direction. On the left extremity of the arm 31 there is fastened a hard steel plate 36 which slightly overlaps said arm. Also, the arm 30 carries on its upper end and opposite this plate 36 a corresponding hard steel plate 37. The arm 31 is normally retained in a position with the member 36 under the member 37 and is latched thereby. In addition, the arm 31 is equipped on its right end with a plunger 38 having a fan-like upper section 39 provided with a slot 40, as shown. This fan-like section 39 is designed for operating in conjunction with a so-called plunger shaft 41 which is controlled by the master switch D. This shaft 41 operates back and forth about an axis through the center 42. The plunger 38 rests against the shaft 41, engaging the ridge 43 which extends along the length of said shaft by the slot 40. The plunger 38 is therefore, normally swung back and forth by the slot 41 about the pivot 44. As shown, the lower end of the plunger 38 carries an insulating member 45 mounted on a small pin 46. As shown in the drawings, the plunger and, therefore, the pin 46 are distorted from their true positions, as is also the case with the springs 47, 48, 49, 50, 51, 52, 53 and 54. These parts are shown diagrammatically and not in their true positions in order that the circuits may be more easily understood. The actual construction is, of course, obvious from the explanation given of the back-and-forth motion. As already explained, the bank of the line switch C comprises a group of bank jacks E, usually ten in number. These bank jacks are arranged in the arc of a circuit to conform with the swinging mo-

tion of the plunger 38, so that the distance between the member 45 and the bank springs is constant, no matter what the position of the plunger 38 may be. The operation of the line switch C is in general as follows: 70 When the trip magnet 19 attracts the armature 30 the plate 37 slips off from the plate 36, and the spring 33 then causes the plunger arm 31 to rotate, so as to thrust the plunger 38 onto the bank jack opposite which it is located at the time, as shown. After the plunger arm thus operates, the plunger shaft 41 of course continues its back-and-forth motion, regardless of the operation of the plunger 38. After thus being operated, the line 75 switch C may be restored by energizing the release magnet 20, which latter attracts its armature 26, thereby raising the trip armature 30 to a height sufficient to enable the plate 37 to be drawn over the plate 36 by 80 the tension of the spring 33. Then when the magnet 20 de-energizes, the spring 28 restores the plunger 38 to engagement with the plunger shaft 41. As indicated by the dotted lines, it will be seen that if the shaft 41 has not by that time returned to the position it originally held when the plunger 38 left the ridge 43, the plunger 38 will not return into locked engagement with the said ridge until such time as the shaft 41 shall 85 have returned to such position. It makes no difference, of course, whether the shaft 41 is traveling one way or the other. Whenever the ridge 43 passes over the notch 40, after the plunger 38 has been withdrawn from the bank, the locking engagement described will thus take place and from thence on the plunger 38 will continue to oscillate back and forth, together with the shaft 41. During the interval between the time when 90 the plunger 38 is released and the time the locking engagement occurs the plunger 38 will remain stationary and opposite the bank jack last used: and if in the meantime the subscriber again makes a call, then the plunger 38 will seize on the same trunk-like. It is to be understood that the springs 48 and 52 of each bank jack are separated by suitable insulating material which is made with a recess, so that while the plunger 95 is in engagement with the banks (as shown in full lines in Fig. 3), or while it is in sliding engagement with the plunger shaft 41 (as shown by the dotted lines in Fig. 3), the plunger 38 is held against turning, because the tip of the plunger 38 is not raised sufficiently to clear the said recess. It is only when the plungers are in locking engagement with the shaft that the tips of the plungers 38 sufficiently clear this insulating 100 material to be able to rotate. 105 The means provided for oscillating the plunger shaft 41 is the master switch D. This master switch is also a comparatively simple device, consisting of an interrupter 110

115 120 125 130

magnet 55 and the interrupter relay 56. This master switch may be mounted upon a frame similar to that described for the line switch C, care being taken that the magnets 55 and 56 are raised high enough to permit the said magnets to operate without interference. The magnet 56 is simply a relay controlling the springs 57 and 58 which are in the energizing circuit for the interrupter 10 magnet 55. The said interrupter magnet 55 may be of any suitable character, such as the one described in United States Letters Patent No. 831,875, granted September 25, 1906 to Alexander E. Keith; but the one 15 herein shown is like the one described in United States Letters Patent No. 841,004, granted January 8, 1907, to John Erickson. This interrupter includes the interrupter springs 59 and 60 and the locking spring 61. 20 These springs are controlled by the interrupter armature 62, which latter carries on its end a pawl 63 for operating the ratchet wheel 64. This ratchet wheel is mounted on an axle 65 perpendicular to the base, and is 25 provided on one side with a plurality of pins 66. These pins are for the purpose of operating a cam 67 which is rigidly secured to the plunger shaft 41. Also secured to the said shaft and cam there is a wiper 68 30 adapted to sweep over the master switch bank contacts *a* and the common member 69, in such a manner that one of the contacts *a* is always maintained in electrical connection with the said member 69. The purpose 35 of the interrupter magnet 65 is to rotate the ratchet wheel 64 in a counter-clockwise direction. This wheel is in addition provided with a stop-pawl 70 to prevent clockwise rotation. It will be seen, therefore, that with 40 this construction while the interrupter magnet 55 operates, the ratchet wheel 64 will be rotated and the shaft 41 and wiper 68 will be advanced step by step until one of the pins 66 clears the cam 67, at which instant 45 said cam is allowed to spring into engagement with the next succeeding pin. The effect of this operation is that the wiper 68 and shaft 41 will advance step by step in one direction and spring back over all of the 50 previously passed contacts by one jump. A preferred arrangement of the master switch bank, as already stated, is shown in Fig. 4, and when the wiper leaves the next to the last contact 71 the wiper 68 clears an insulated spring 72 over which it slides at the return jump instead of passing over the contacts *a*. It will be seen that when the wiper 68 arrives opposite the first contact 73, the wiper 68 again jumps into engagement with 55 the said first contact 73. It will be seen, therefore, that the position of the wiper 68 relative to the bank contacts *a* shows the position of all plungers that are in locked engagement with the plunger shaft 41. It will 60 be assumed that when the wiper 68 is op-

posite the first contact 73 all plungers in locked engagement with the plunger shaft will be found opposite the multiple bank jacks which are terminals of the trunk-line leading to the first-selector F. Therefore, 70 the plunger 38 if thus locked will be opposite the bank jack E. As shown in Fig. 1, every trunk-line leading from the line switch banks, such as the one terminating in the first-selector F and comprising the conductors 74 and 75, is provided with means for automatically releasing the line switch C whenever the subscriber's line is opened after the switch has been operated. This means comprises a double-wound relay 76 80 having windings 77 and 78 and a relay 79 for controlling the circuit through the commutator interrupter 80.

The first-selector F is a modified form of the selector switch disclosed in United States Letters Patent No. 815,321, granted March 13, 1906, to Keith, Erickson & Erickson—that is, it is a modified form as far as the circuits are concerned, the mechanical aspect of the switch being the same with one exception, namely in the patent to which reference is made the release magnet does not produce the release until it deenergizes, but in the first-selector of my present invention this release has been changed to the form described in United States Letters Patent No. 815,176, also granted March 13, 1906, to Keith, Erickson & Erickson. The release is such that as soon as the release magnet energizes, the connector switch shaft and side switch are restored. For example, the switch F is provided with a switch shaft (not shown) which carries the line and private wipers 81 and 82, and 83. Instead of having two line relays, as is ordinarily the case, this selector is provided with one double-wound line relay 84. In addition, the said selector comprises a slow-acting relay 85 known as the private magnet relay, and another slow-acting relay 86 known as the releasing relay. The vertical magnet 87, the rotary magnet 88, the release magnet 89 and the private magnet 90 are well known and in general operate the same as the magnets of the selector patent. The said private magnet, of course, controls the side switch wipers 91, 92, 93 and 94. These relays may be made slow-acting in any manner known to the art, for example, by providing each relay with an additional low-resistance winding closed upon itself, or by providing each relay with a copper shield, which copper shield is indicated in the drawings by the small squares at the top of the coils.

The first-selector H is substantially the same as the first-selector F. It is equipped with the same number of magnets, namely the line relay 95, the private magnet 96, the releasing relay 97, the release magnet 98, the vertical magnet 99, the rotary magnet 100

and the private magnet 101. The circuits, however, are a trifle different at certain points, which differences will be explained hereinafter.

6 The connector switch I is a modified form of the connector switch disclosed in United States Letters Patent No. 815,176, granted March 13, 1906, to Keith, Erickson & Erickson. Its modification relates mainly to the 10 circuits, the mechanical features of the connector switch I being practically the same as those of the connector of the said patent. For example, the connector switch I is provided with the usual switch shaft (not 15 shown) that carries the line and private wipers 102 and 103, and 104. Like the selectors F and H, the connector switch I instead of having two line relays, as is usually the case, is provided with one double-wound relay 105. It also has a slow-acting relay 106 known as the release relay, and another slow-acting relay 107 known as the private magnet relay. This relay also controls the busy 20 circuit and the circuit of the well-known rotary magnet 109. The vertical magnet 110, the release magnet 111, the ringer relay 112, the private magnet 113 and the back-bridge relay 114 are well known. It will be seen 25 that the connector is also provided with the usual condensers 115 and 116 which are included in the talking circuit and which divide the said talking circuit into inductively-connected sections. At the exchange there 30 is also provided a ringer generator 117, a 35 commutator circuit interrupter 118 for controlling the ringer relay circuit, a busy transformer 119, and a commutator circuit interrupter 120 for the busy transformer. It 40 will be evident, of course, that if it is desired these commutator interrupters 118 and 120 may be consolidated into one.

The line-switch C' being the same as the line switch C, the release magnet 121, the trip magnet 122, and the cut-off relay 123 will, of course, be recognized. At the 45 exchange there is also provided a common relay 124 (Fig. 1) for the purpose of supervision, and to indicate to the exchange attendant whenever a subscriber's line is 50 grounded. A similar relay 125 is shown in connection with the line switch C'. These 55 relays may be allotted one to each group of subscribers or one to each of the subscribers. When energized they are adapted to close a signal circuit of any character, such as bell, lamp, or both.

Having thus described the general character of the apparatus which is used in the system I will now describe the process by 60 which the calling subscriber A (Fig. 1) establishes connection, signals and converses with the subscriber at substation A' (Fig. 2), and also the method by which the apparatus is restored to normal condition after 65 being brought into use. Assuming this to

be a ten-thousand subscriber system, the substation A' will be designated as #2220; and in order to call the said substation the subscriber at substation A must operate his dial four times in accordance with the digits 2, 2, 2 and 0. As soon as the subscriber removes his receiver 2 the switch-hook 6 is permitted to rise, whereby the springs 15 and 16 are brought into contact. The circuit is thereby closed, including the trip magnet 19 and the common relay 124. Said circuit extends from ground G¹ through the trip magnet 19, and through the cut-off relay springs 25 and 24 to the rotary line conductor 125, thence through the springs 15 and 16, and through the interrupter springs 12 and 11, through the transmitter 3 to the vertical line conductor 127, thence through the cut-off relay springs 22 and 23 and the relay 124 to the battery lead 128, thence through battery B to ground G. The trip magnet 19 then attracts its armature 30 (see Fig. 3), thereby causing the plunger 38 to trip onto a bank jack E, assuming that the plunger 38 is opposite the said bank jack at the time. As soon as this plunger operates, as described, it presses the bank springs 54 and 53, 50 and 49, 47 and 48, and 52 and 51 into contact. The closure of contact between the springs 47 and 48, it will be seen, 80 closes an energizing circuit through the bridge-cut-off relay 21 which extends from ground G² through the springs 47 and 48, conductor 129, through the relay 21 to the battery lead 128, thence through battery B to ground G. The cut-off relay thus separates the cut-off relay springs, thereby breaking the originally established circuit through the trip magnet 19 and the common relay 124. Attention will be called to the 90 fact that this operation is so quick—that is, the tripping operation of the line switch C—that the relay 124 remains energized but for a very short interval of time, and too short for establishing an alarm of the character described in the preceding explanation. The closure of contact between the bank springs 54 and 53 extends the subscriber's vertical line conductor 127 into contact with the trunk conductor 74, and the closure of 100 contact between the bank springs 52 and 51 places the rotary line conductor 126 in contact with the rotary trunk conductor 75. As a result an energizing circuit is established through the line relay 84 of the first-selector 105 F. This energizing circuit extends from ground G³ through the winding 130 of the line relay 84, contact point 131, side switch wiper 92, trunk conductor 75, winding 78 of the trunk relay 76, bank springs 51 and 52 to 115 the rotary line conductor 126, thence through the substation A to the vertical line conductor 127 over the springs 54 and 53, through the winding 77 of the trunk relay 76 to the trunk conductor 74, thence through the side 120

switch wiper 91, contact point 132, winding 133 of the line relay 84 to the battery lead 128, thence through battery B to ground G. The closure of this circuit causes the line relay 84 to energize, the windings 130 and 133 being in series, whereby the spring 134 is separated from the spring 135 and carried into engagement with the spring 136, with the result that the slow-acting releasing relay 86 energizes and in turn operates to shift the spring 137 from the spring 138 and into engagement with the spring 139. The energizing circuit for the slow-acting relay 86 extends from ground G⁴ through the line relay 86 to the battery lead 128, thence through battery B to ground G. It will be understood that the relays spoken of as slow-acting relays in this specification are slow-acting only as far as de-energizing is concerned. These slow-acting relays are capable of energizing almost as quickly as the other relays. When the line relay 84 energizes, as described, the line relay spring 135 it will be seen, is placed in connection with the slow-acting private magnet relay 85, and through the said relay with the vertical magnet 87, whereby ground impulses may be sent from the said spring 135 through the said magnets 85 and 87 while the relay 86 is energized. Attention is called to the fact that the trunk relay 77 is a slow-acting relay and energizes at the same time that the line relay 84 energizes and over the same circuit. This relay, therefore, operates when connection is established with the selector F, as described, to separate the springs 140 and 141. The foregoing having been accomplished by the subscriber in the act of removing his receiver from the switchhook, he then continues the call by operating his dial for the first digit 2.

When the dial is drawn down the impulse wheel 7 is rotated so that two of the impulse teeth 9 are carried beyond the lug 10 on the spring 11; then as the dial returns, the said teeth operate to twice separate the spring 11 from the spring 12. Each time that the said springs are separated the energizing circuit for the relays 77 and 84 is interrupted; but since the relay 77 is slow-acting the said relay is not given time to de-energize between impulses. It is to be understood that the impulse wheel 7 operates at such a rate as to produce such a result. In this system the subscribers are instructed that when the dial is drawn down it should be absolutely released and allowed to return unimpeded, or if desired a telephone with a protected dial, such as the one described in the application of John Erickson, Serial No. 331,700, filed August 23, 1906, may be used. Each time that the circuit is interrupted at the springs 11 and 12, as described, the armature of the line

relay 84 of the selector F falls back and permits the spring 134 to come into contact with the spring 135, and impulses are transmitted from ground G⁴ by way of the springs 134 and 135 of the line relay, and the springs 137 and 139 of the slow-acting release relay 86, through the private magnet relay 85 and through the vertical magnet 87 to the side switch contact point 142, thence over the side switch wiper 94 to the battery lead 128, thence through battery B to ground G. As already explained, the trunk relay 77 does not have time to de-energize while the line relay 84 is operated, and the same is true of the release relay 86. This relay 86 is so built that the customary interruptions of the circuit at the point between the line springs 134 and 136 are not of sufficient duration to permit the said relay 86 to be de-energized. The first impulse transmitted by the line relay 84 over the circuit described causes the private magnet relay 85 to energize, and said relay remains so during the succeeding impulses owing to its slow-acting character. Upon energizing, the said slow-acting relay 85 presses the springs 143 and 144 into contact, whereby the private magnet 90 is energized by a flow of current from ground G⁴ through said springs 143 and 144, and through the said private magnet 90 to the battery lead 128, thence through battery B to ground G. The said private magnet 90, of course, remains energized as long as the slow-acting relay 85 is energized. The impulses produced by the line relay 84, of course, also energize the vertical magnet 87, which vertical magnet 87 then operates to raise the switch shaft one step for each impulse. Since two impulses are transmitted to the shaft, the vertical, line and private wipers 81, 82 and 83 are raised two steps and brought opposite the first contacts of the second bank level of the selector F. It will be seen that when the impulse wheel 7 ceases to operate the spring 11, the line relay 84 again resumes its constant energized condition, so that the private magnet relay 85 de-energizes, whereby the springs 143 and 144 are allowed to separate, and the private magnet 90 as a result allowed to de-energize, which private magnet then allows the side switch to trip to second position. As soon as the side switch trips to second position the side switch wiper 94 engages the contact point 145, thereby establishing an energizing circuit for the rotary magnet 88 extending from ground G³ through the interrupter spring 146, through the rotary magnet 88 to the contact point 145, thence through the side switch wiper 94 to the battery lead 128, and through battery B to ground G. The rotary magnet then attracts its armature, rotating the shaft one step and thus causing the line

wipers to engage the contacts of the first trunk-line in the second level. The interrupter used in connection with this rotary magnet may be of any suitable character, but preferably it is of the character shown and described in said letters Patent No. 841,004 and No. 831,875. As disclosed in said selector Patent No. 815,321, when the rotary magnet 88 attracts its armature the 5 armature of the private magnet 90 is operated at the same time by the usual private armature finger carried by the rotary armature. The result is that the first step or operation of the rotary magnet not only 10 rotates the shaft wipers into engagement with the first trunk-line, but as the rotary armature falls back the private armature is also permitted to fall back, at which time the side switch trips to third position. This is 15 only true if the first trunk is idle, which trunk, it is assumed, terminates in the second-selector H. It will be seen that when the side switch passes to third position the side switch wiper 93 engages the contact 20 point 149, whereby the private wiper 83 is placed in connection with ground G⁴, since the line relay 84 is energized. The circuit over which this connection is maintained is as follows: from ground G⁴ 25 through the line relay springs 134 and 136, conductor 150 to the contact point 149, thence to the side switch wiper 93 and over the conductor 147 to the private wiper 83. The private wiper 83 being in engagement 30 with one of the multiple private bank contacts corresponding to the trunk-line terminating in the selector H, all of the multiple private bank contacts connected thereto are thus provided with a guarding potential for preventing other selectors from 35 ringing the same trunk-line. If the first trunk is busy, however, the armature of the private magnet does not fall back with the rotary armature at the end of the first 40 step, but is retained by the private magnet which is then energized by a flow of current over a circuit which is closed as soon as the private wiper 83 engages a grounded contact, whereby an energizing circuit is 45 set up through the private magnet 90 extending from this grounded private bank contact through the wiper 83, over the conductor 147 to the side switch wiper 93, thence to the contact point 148, and through 50 the private magnet 90 to the battery lead 128, thence through battery B to ground G. It will be seen, therefore, that the private magnet 90 will retain the side switch locked in second position as long as the private 55 wiper 83 encounters busy trunk-lines, on account of the connection maintained between each private bank contact of a busy line and ground. However, as soon as the rotary magnet 88 advances the wipers onto an idle 60 trunk-line, the energizing circuit for the private magnet 90, including the private wiper 83, is broken at this wiper, and as a result the privet magnet 90 will de-energize at the last stroke of the rotary magnet, permitting the side switch to pass to third 65 position. As soon as the side switch passes to third position a guarding potential is established at the private wiper 83 and, therefore, at all private bank multiple contacts, as already explained. It will be assumed 70 that the first-selector F stops on the first trunk-line, as previously explained; then when the side switch passes to third position the side switch wipers 91 and 92, upon engaging the third-position contacts 151 and 152, respectively, extend the trunk conductors 74 and 75 to the trunk conductors 153 and 154 which terminate in the second-selector H. It will be evident that when 75 the side switch of the first-selector is in first position the wipers 91, 92, 93 and 94 are in engagement with the contact points 132, 131, 155 and 142; when in second position they are in engagement with the contact points 156, 157, 148 and 145; and when 80 in third position the wipers are in engagement with the contact points 151, 152, 149 and 158. It will be seen that when the side switch thus passes to third position the energizing circuit for the line relay 84 85 of the selector F is cut off and, therefore, the said relay is restored. It will be seen, of course, that the energizing circuit for the line relay 84 cannot be broken until the side switch passes to third position, because the side switch contact points 132 and 156 are connected on one side, and the side switch contact points 131 and 157 are likewise connected on the other side. It 90 follows, therefore, that the connection to ground G⁴ is interrupted at a point between the line relay springs 134 and 136, and a guarding potential is established at the private bank contact engaged by the private wiper 83 from the selector H, as follows: As soon as the side switch trips to 95 third position, as explained, the line relay 95, like the line relay 84, energizes over the following circuit: from ground G⁵ through the winding 159 of the relay 95, to the side switch wiper 160 of the second-selector H, thence to the trunk conductor 154, rotary line wiper 82 of the second-selector F, contact point 152, side switch wiper 92, through the substation A, back 100 on the other side of the line to the first-selector side switch wiper 91, contact point 151, vertical line wiper 81 to the side switch wiper 161 of the second-selector H, thence through the winding 162 of the line relay 105 95 to the battery lead 128, thence through battery B to ground G. The line relay 95 being similar to the line relay 84, the spring 163 is separated from the spring 164 and carried onto the spring 165. As a result 110

the slow-acting release relay 97 is energized by a flow of current from ground G⁶ through the springs 163 and 165, release relay 97 to the battery lead 128, thence 5 through battery B to ground G.

The slow-acting relay 97, upon operating, shifts the spring 166 from the spring 167 into contact with the spring 168, similar to the slow-acting relay 86. This relay 97, 10 however, has two additional springs 169 and 170 which are pressed into contact at the same time, whereby a ground connection is substituted at the private wiper 83 from the ground G⁷ in place of the ground G⁴. 15 This is evident since the side switch of the selector H is in first position. Not only will this be true while the side switch is in first position, but also when it is in second position, as indicated by the side switch contact points 171 and 172 being connected. 20 The calling subscriber having thus extended his connection to the second-selector H, he operates his dial in accordance with the second digit 2, with the result that the line relay 95 is operated twice and the spring 163 carried twice into engagement with the spring 164 while the slow-acting relay 97 is 25 energized. The result is that at the first impulse the slow-acting private magnet relay 96 is energized and the vertical magnet 99 operated once. The slow-acting relay 96, of course, remains energized until the second 30 impulse is sent, which again operates the vertical magnet 99 through the slow-acting relay 96. In this way the switch shaft of 35 the second-selector H is raised two steps by the vertical magnet 99, and the line and private wipers 173 and 174, and 175 are placed opposite the first contact of the second level of the second-selector bank. It 40 will be evident, of course, that as soon as the slow-acting relay 96 energizes, the springs 176 and 177 are pressed into contact and an energizing circuit established for 45 the private magnet 101 from ground G⁶ through the springs 176 and 177 and through the private magnet 101 to the battery lead 128, thence through battery B to ground G. The private magnet, of course, 50 attracts its armature, but does not release the side switch to second position until all the impulses have been sent in, after which the slow-acting relay 96 de-energizes, as in the first-selector F, which then interrupts 55 the circuit between the springs 176 and 177. It will be seen that the energizing circuit for the vertical magnet 99 and for the slow-acting relay 96 extends from ground G⁶ through the line relay springs 163 and 164, 60 through the relay springs 166 and 168 to the private magnet relay 96, thence to the vertical magnet 99, side switch contact point 178, side switch wiper 179 to the battery lead 128, thence through battery B to ground G. 65 When the side switch passes to second posi-

tion the side switch wiper 179 engages the contact point 180, thus closing the energizing circuit for the rotary magnet 100 from ground G⁵ through the interrupter spring 181, rotary magnet 100, side switch contact 70 point 180, side switch wiper 179 to the battery lead 128, thence through battery B to ground G. It will be seen that in the selector H, as in the selector F, at the first impulse through the rotary magnet 100 the 75 armature of the private magnet 101 is operated to trip the side switch to third position, provided the first trunk-line is idle, by which operation the subscriber's line is placed in connection with the connector 80 switch I. However, if the first trunk-line is not idle the private wiper 175 will be carried onto grounded contacts, as described in connection with the first-selector F, with the result that the private magnet 101 is 85 energized and maintained energized for the purpose of locking the side switch in second position until the rotary magnet has advanced the shaft and wipers beyond the last busy trunk, at which time the private magnet de-energizes and permits the side switch to pass to third position, with the usual result. In the second-selector H it will be seen that the side switch comprises the 90 wipers 179, 161, 160, 182 and 183. The 95 shaft wipers 173, 174 and 175 having been rotated into engagement with the trunk conductors 184, 185 and 186, then when the side switch wipers 161 and 160, upon passing to third position, engage the side switch 100 contact points 187 and 188 the circuit is extended to the connector switch I. The connector line relay 105 instantly energizes, the current flowing from ground G⁸ through the winding 189 of the line relay 105 to 105 the trunk conductor 185, rotary line wiper 174 of the second-selector H, contact point 188, side switch wiper 160, over the rotary side and through the first-selector F, line switch C and telephone A to the vertical 110 side, back through the line switch C, first-selector F and second-selector H to the side switch wiper 161, contact point 187 vertical line wiper 173, vertical trunk conductor 184, winding 190 of the line relay 105, 115 through the release relay 106 to the battery lead 128, thence through battery B to ground G. As soon as the slow-acting relay 106 energizes it operates to shift the spring 191 from the spring 192 and into engagement with the spring 193, and at the same 120 time operates to close the springs 194 and 195 in contact. As soon as the springs 194 and 195 close in contact a guarding potential from ground G⁹ is applied to the trunk-release conductor 186, to take the place of the guarding potential removed from the private wipers 175 and 83, by the shifting 125 of the second-selector side switch wiper 182 away from the contact point 172 at the in- 130

stant that the second-selector side switch trips to third position. This guarding potential, it will be seen, also maintains the slow-acting relays 97 and 86 energized, the energizing circuits being as follows: from ground G^9 at the connector I to the contact point 196, side switch wiper 197, trunk-release conductor 186, private wiper 175, conductor 198, second-selector side switch 10 wiper 183, conductor 199, slow-acting relay 97 to the battery lead 128, thence through battery B to ground G. The slow-acting relay 86 is energized over a branch circuit as follows: from the private wiper 175 15 through the side switch wiper 183 at the second-selector H, conductor 200, trunk-release conductor 201, private wiper 83, conductor 147, side switch wiper 93, conductor 150, through the relay 86 to the battery lead 128, thence through battery B to ground G. The closure of contact between the release relay springs 191 and 193, it will be seen, extends connection between the line relay spring 202, the vertical magnet and the rotary magnet 109. When the line relay 105 20 attracts its armature it will be seen that the spring 202 is separated from the spring 203 and carried into engagement with the spring 204 with no result. However, when the subscriber proceeds by operating his dial for the third digit 2, the line relay 105 operates exactly as the line relays of the selector switches F and H have operated, permitting the spring 202 to fall back onto 25 the spring 203 a number of times corresponding to the digit. Each time that the circuit is closed between the springs 202 and 203 the vertical magnet 110 is energized once, raising the switch shaft each time. The energizing circuit through the said magnet, it will be seen, extends from ground G^{10} through the line relay springs 203 and 202, through the release relay springs 191 and 193 to the vertical magnet 110, thence 30 to the contact point 205, side switch wiper 206, private magnet relay 107, thence through said relay to battery lead 128, and through battery B to ground G. At the first impulse the private magnet relay 107, being a slow-acting relay, remains energized during the interval in which the remaining impulses are transmitted to the vertical magnet 110. At the end of this operation the shaft wipers 102, 103 and 104 will be found 35 opposite the first contact of the second level of the connector banks. It will be seen that, upon energizing, the slow-acting private magnet relay 107 separates the springs 207 and 208, and carries the spring 209 into engagement with the spring 210. The closure of contact between the springs 210 and 209 energizes the private magnet 113 by a flow 40 of current from ground G^{11} through the springs 210 and 209 and through the said private magnet 113, thence through battery 45 B to ground G. When the line relay 105 ceases to operate, the slow-acting relay 107 de-energizes, and as a result the private magnet 113 also de-energizes. As a result the side switch, as is well known, passes 50 to second position, whereby the side switch wipers 211, 212, 205, 197 and 213 pass from the contact points 214, 215, 205, 196 and 216 into engagement with the contact points 217, 218, 219, 220 and 221. The subscriber 55 is now ready to operate his calling device for the last digit 0. He does so and thereby transmits to the central office ten impulses, thereby operating the line relay 105 ten times. Each time that the line relay 60 springs 203 and 202 engage, an energizing circuit is established through the rotary magnet 109 from ground G^{10} through the said springs 203 and 202, springs 191 and 193, through the rotary magnet 109 to the 65 contact point 219, thence through the side switch wiper 206, and through the private magnet relay 107 to the battery lead 128, thence through battery B to ground G. Again the private magnet relay energizes, as 70 in the previous case, remaining so until all the rotary impulses are transmitted, thereby retaining the private magnet also energized. The rotary magnet 109 then operates to rotate the shaft wipers into engagement with the desired line #2220. If this line is busy at the time, the connector switch will be given the busy release, and the calling subscriber is given the busy-signal, thus making it impossible to extend the calling line into 75 connection with the called line. 80

Before describing the results that follow when the connector finds a busy line, the description of how a connection is established will be completed. As soon as the line relay 105 ceases to operate for the last digit the private magnet relay 107 de-energizes, as heretofore explained, in this instance permitting the side switch to trip to third position. The result is that the side switch 85 wipers 211, 212, 206, 197 and 213 engage the contact points 224, 225, 226, 227 and 228, respectively. When the side switch wiper 213 engages the contact point 8 a guarding potential is extended to the private 90 wiper 104 for protecting the seized line from outside interference while the connection is established. This guarding potential extends from ground G^{12} to the contact point 228, thence by way of the side switch 95 wiper 213, conductor 229 to the private wiper 104. Not only does this guarding potential prevent other connectors from seizing the same line over multiples of the normal conductors 232 and 233 and 234, but it 100 also provides means for energizing the cut-off relay 123 of the line switch C', whereby said switch C' is prevented from operating when the called subscriber removes his receiver from the switch-hook 236. It will 105

also be seen that when the side switch passes to third position the trunk-release conductor 186 that extends from the second-selector to the connector (Figs. 1 and 2) is provided with guarding potential from ground G^{10} through the line relay springs 202 and 204, contact point 227, side switch wiper 197, release relay springs 194 and 195 to the trunk conductor 186. However, while the side switch is in first and second position a guarding potential for this trunk 186 is provided from ground G^9 . The reason for this is that the guarding potential from ground G^{10} is interrupted while the line relay 105 is operating, and there is some liability of some other selector, similar to the second-selector H, stopping on the same trunk-line. After the side switch passes to third position, however, there is no such danger, and the potential is provided from ground G^{10} only, as stated. Of course, when the side switch wipers 211 and 212 engage their third-position contact points 224 and 225, the calling subscriber's line is placed in connection with the called subscriber's line over the heavy conductors shown as passing through the ringer relay springs 237 and 238 on one side and 239 and 240 on the other side. As soon as connection is thus established the ringer relay 112 is energized over the circuit established when the side switch wiper 206 engages the contact point 226, the energizing current flowing from ground G^{13} through the interrupter 118, through the back-bridge relay springs 241 and 242, ringer relay 112, conductor 243, contact point 226, side switch wiper 206, slow-acting relay 107 to the battery lead 128, thence through battery B to ground G. It will be seen that as the interrupter 118 revolves, the energizing circuit of the ringer relay 112 will be broken periodically so as not to ring the called subscriber continuously. However, as soon as the called subscriber answers, the back-bridge relay 114 is energized by a flow of current from ground G^{12a} , winding 244 of the back-bridge relay 114, conductor 245, ringer relay springs 240 and 239, side switch wiper 212, contact point 225, rotary line wiper 103, rotary normal conductor 233, rotary line conductor 246, switch-hook springs 247 and 248, impulse springs 249 and 250, transmitter 251, vertical line conductor 252, vertical normal conductor 232, vertical line wiper 102, contact point 224, side switch wiper 211, ringer relay springs 237 and 238, conductor 253, winding 254 of the back-bridge relay 114, thence to the battery lead 128, and through battery B to ground G. It will be seen that each time that the ringer relay is energized the springs 239 and 237 are separated from the ringer relay springs 240 and 238, thereby breaking the calling line from the called line, and pressing the

springs 237 and 239 onto the springs 255 and 256 which are the terminals of the ringer generator 117. As a result ringing current is sent over the called line for energizing the bell 257 while the springs 247 and 258 are in contact. Once the back-bridge relay 114 is energized, however, the energizing circuit for the ringer relay 112 is interrupted at a point between the springs 242 and 241, thus making it impossible for the ringer relay to energize as long as the called subscriber is on the line. The subscribers being thus connected, they may communicate over the main talking conductors indicated by the heavy lines and including on one side the condenser 115 at the connector I and on the other side the condenser 116. This talking circuit also includes the windings 77 and 78 of the trunk coil 76. For the purpose of clearing the talking circuit of the impedance of these coils the condensers 259 and 260 are arranged across the said windings, as shown.

I will now describe the use of the master switch D and its operation. It was assumed in the beginning that the master switch wiper 68 was resting on the bank contact 73 and, therefore, that the plunger 38 was opposite the bank jack E. The calling subscriber then removed his receiver, causing the line switch to operate, which, as explained, throws the springs 49 and 50 into contact as a result, and the bank contact 73 is placed in connection with the non-grounded terminal of battery B through the release magnet 20 of the line switch C. This circuit, it will be seen, extends from the non-grounded terminal of battery B to the battery lead 128, thence through the release magnet 20, and through the said bank springs 50 and 49 to the bank contact 73 (see Fig. 3). The wiper 68 maintaining the contact 73 in electrical connection with the common member 69, a circuit is established which extends through the relay 56, by way of the said wiper 68, to the member 69, thence through the winding 262 of the relay 56 to ground G^{16} , and back to battery B. The relay 56, upon energizing, closes the springs 57 and 58 in contact, thereby closing an energizing circuit for the rotary magnet 55 from ground G^{17} through the springs 58 and 57, interrupter springs 59 and 60 and rotary magnet 55 to the battery lead 128, thence through battery B to ground G. The said rotary magnet then operates to rotate the ratchet wheel 64 one step, thereby advancing all idle plungers in locking engagement with the plunger shaft 42 to a position opposite the second bank jack, and advancing the wiper 68 into engagement with the second contact 263. If the trunk-line corresponding to this bank contact 263 is idle, the energizing circuit for the rotary magnet relay 56 is at once interrupted, so

that the master switch does not advance any further. If, however, the next trunk-line is busy, the contact 263 will be found connected with the non-grounded terminal of battery B exactly as the contact 73 has been described, and, of course, the relay 56 cannot be deenergized, but maintains the energizing circuit through the rotary magnet 55 until the wiper 68 is advanced into engagement with some contact which is not protected. The master switch is thus advanced one step each time a subscriber's line switch seizes a trunk-line, until the wiper 68 is carried onto the last contact 264, clearing the spring 72, as shown in Fig. 4. When the next subscriber makes a call the pin 66 clears the cam 67 and the wiper 68 is caused to jump back over the upper side of the spring 72 until said spring 72 is cleared, at which instant the wiper 68 again springs back onto the first contact 73. Of course, if this contact 73 is busy the relay 56 will energize the rotary magnet 55 in a manner and for the purpose already explained. It will be apparent, then, that if the subscriber A has released before the wiper 68 reaches the first contact 73 again, the plunger 38 will be free to fall back into locking engagement with the shaft 41. It should be understood that the plunger 38 and the plunger shaft 41 are so light that even during the quick passage of the wiper 68 from the last contact 64 to the first contact 73, any plunger 38 that has been released will be caught and retained by the plunger shaft 41. After the subscribers are through talking, if the calling subscriber hangs up his receiver he opens up the line circuit at a point between the springs 15 and 16, thereby initiating the release of all of the switches. This release is as follows: At the instant that the circuit is broken between the said springs 15 and 16, the double-wound trunk relay 76 de-energizes, permitting the springs 140 and 141 under its control to come into contact. This establishes an energizing circuit for the relay 79 over a path extending from ground G¹⁴ through the relay 79, through the springs 141 and 140 to the bank spring 49, thence through the release magnet 20 of the line switch C to the battery lead 128, thence through battery B to ground G. As soon as the relay 79 draws the springs 265 and 263 into contact a release circuit is established through the release magnet 20, said circuit extending from ground G¹⁵ through the interrupter 80 and through the springs 265 and 266 to the line switch bank springs 49 and 50, thence through the release magnet 20 to the battery lead 128, thence through battery B to ground G. It will be seen that the release magnet will then energize and, as previously explained, cause the trip armature 30 to fall over the plunger arm 31, whereby the members 37 and 38 engage (see Fig. 3). As the interrupter 80 continues to revolve, the release circuit is broken for an instant, which permits the release magnet 20 of the line switch C to de-energize, thereby withdrawing the plunger 38 from the bank jack E. As a result the bank springs 49 and 50, as well as the other bank springs of the line switch C, are separated, thus preventing any further electrical impulses from coming in from the trunk. At the same time the line relay 105 and the release relay 106 of the connector I de-energize, being in series with each other and with the line. At the instant that the slow-acting relay 106 and the line relay 105 de-energize, the energizing circuit for the release magnet 111, is closed at a point between the springs 191 and 192, and at another point between the springs 202 and 203. A flow of current is, therefore, set up from ground G¹⁰ through the springs 203 and 202, through the springs 191 and 192 to the release magnet 111, thence through said magnet to the off-normal spring 267, to the contact point 268 and to the battery lead 125, thence through battery B to ground G. The release magnet instantly releases the connector switch shaft and side switch, thereby breaking the energizing circuit through the back-bridge relay 114, if the called subscriber has not in the meantime restored his receiver, and also the energizing circuit through the bridge-cut-off relay 123 of the called line switch C'. As soon as the connector switch shaft reaches its lowest position it breaks the circuit for the release magnet 111 by separating the off-normal spring 267 from the contact point 268, at which instant the release magnet of the connector is also restored. The operation of the line relay 105 and of the slow-acting relay 106 not only causes the release of the connector, as described, but also the release of the preceding switches, because the ground connection from ground G⁹ to the trunk-release conductor 186 is interrupted by both of these relays. Since the release relays 86 and 97 are dependent upon that ground for their energized condition, as already explained, it follows that they will fall back with the following results: As soon as the release relay 97 of the second-selector H de-energizes, the spring 166 falls back into normal engagement with the spring 167, thereby closing an energizing circuit for the release magnet 98 from ground G⁶ through the springs 163 and 164, and through the springs 166 and 167 to the release magnet 98, thence to the contact point 269, off-normal spring 270 to the battery lead 128, thence through battery B to ground G. As soon as the release magnet 98 energizes, the second-selector side switch and switch shaft are restored, which switch shaft, upon reaching its lowest position, opens up a release

circuit at a point between the off-normal spring 270 and the contact point 269, whereby the release magnet 98 is also restored. When the release relay 86 of the selector F de-energizes, the springs 137 and 138 are brought into contact, and as a result the energizing circuit for the release magnet 89 is closed. The energizing current for this release magnet 89 then flows from ground G⁴ through the springs 134 and 135, and through the said springs 137 and 138 of the release magnet 89, thence through said magnet to the contact point 271, off-normal spring 272 to the battery lead 128, thence through battery B to ground G. The release magnet, upon energizing, then restores the first-selector side switch and switch shaft, which switch shaft, upon reaching its lowest position, opens the energizing circuit for the release magnet 89 at a point between the off-normal spring 272 and the contact point 271. After the switches are thus restored, the calling subscriber can, of course, then proceed to make another call.

25 Returning now to that stage of the call where the calling subscriber was operating the connector switch in accordance with the last digit 0, it will now be explained what takes place in the event that the desired line 30 is busy. When the line #2220 is calling, or when it has been called by someone else, the private bank contacts in which the normal conductor 234 terminates are connected to ground. If another connector switch has 35 called the line, this guarding potential would be supplied through the connector switch from a ground terminal similar to the ground terminal G¹² in the connector switch I, as already explained but 40 if the line switch C' is calling, a guarding potential is established from ground G¹⁸ through the bank springs 273 and 274 to the private normal conductor 234, thence to the private bank contact. In a similar manner the line switch C protects the calling line A when the bank springs 47 and 48 come into contact from ground G², from 45 which ground connection is established through the said bank springs to the private normal conductor 275. Therefore, when the 50 subscriber sends in the last impulse the private wiper 104 is carried onto the grounded contact, and when the slow acting relay 107 of the connector de-energizes, the springs 55 207 and 208 engage, closing an energizing circuit through the release magnet 111. This circuit extends from the grounded private bank contact to the private wiper 104, side switch wiper 213, contact point 221, springs 207 and 208, release magnet 111, normal springs 267 and 268 to the battery lead 18, thence through battery B to ground G. The connector release magnet, upon energizing, operates to restore the switch to 60 normal position, whereby the normal 65

springs 267 and 268 are disengaged, destroying the energizing circuit of the release magnet. The springs 281 and 282 are pressed into contact when the shaft returns to normal position, thus connecting the 70 busy-signaling circuit with the calling subscriber's line conductors as follows: from the primary winding of the busy coil 119 through the springs 282 and 281 to the rotary line conductor 185, through the substation A to the vertical side of the line, then over said vertical side back to the connector I, through the winding 193 of the line relay 105 to the relay 106, and through battery B to ground G, thence to the interrupter ground 80 G²⁰, through the interrupter 120 to the primary winding of the busy coil 119 back to the secondary winding. When the calling subscriber receives the busy-signal he understands that the line is busy and hangs up his receiver. The line circuit is open, as already explained, with the result that the line and slow-acting relays 105 and 106 of the connector I de-energize, causing the release of the connector and all other switches, as heretofore explained.

90 From the foregoing description it will be evident that if the line switch C should be tripped onto the trunk that terminates in the first-selector F, and if the conductors leading from the line switch bank springs 53 or 51 should be broken, the line switch C will instantly be released for the following reasons: Unless the trunk conductors 74 and 75 leading from the said springs 53 and 51 are intact, it will be impossible to 95 energize the trunk relay 77; consequently the trunk relay springs 140 and 141 would remain in contact after the bank springs 49 and 50 engage, and the release relay 79 will 100 energize through the springs 141 and 140, and 49 and 50, as already explained, with the result that the release circuit through the release magnet 20 of the line switch C is established from ground G¹⁵ through the interrupter 80 and through the springs 266 and 265, springs 49 and 50, through the release magnet 20, and through said magnet to the battery. The effect of establishing this 105 release circuit has already been described as 110 producing the release of the line switch C. The same is true with regard to the first-selector F—that is, if the first-selector F stops on the trunk-line leading to the second-selector H, for example, and this trunk-line happens to be open—that is, if either of the 115 trunk conductors 153 or 154 are open—the release relay 86 cannot be maintained energized, because the line relay 95 of the second-selector H cannot energize, since the line is open, and since the line relay 95 cannot energize the line relay springs 163 and 165 are not brought into contact to supply 120 ground to the trunk-release conductor 201 for maintaining the release relay 86 ener- 125 130

gized. Therefore, as soon as the release relay 86 de-energizes the release magnet 89 will then energize, as heretofore explained, with the result that the switch is restored.

5 It will be seen that the release magnet 89 of necessity energizes, since at the time the switch shaft is off normal the off-normal spring 272 is in engagement with the contact 271. The energizing circuit for the release magnet, it will be seen, is also dependent upon the de-energized condition of the line relay 84, which relay is de-energized at the time, because the side switch is in third position. Not only will the first-
10 selector F be released, but the line switch will likewise be released at the instant that the second-selector side switch trips to third position, since in that event the trunk relay 77 de-energizes, because of the open line between the selector F and the selector H. It will therefore be seen that an open trunk between a first-selector and a second-selector will cause the release of all switches up to that point, if the first-selector seizes the
15 said open trunk. Also, if the trunk-release conductor 201 running from the first-selector F to the second-selector H is open when the first-selector stops on the trunk, it will be seen that the first-selector F will be released, because there is no connection to ground to maintain the release relay 86 energized. Of course, the line switch C will not be released in this case, because as soon as the first-selector side switch is tripped to
20 first position, and since the subscriber's receiver is off the hook at the time, the trunk relay 77 is retained energized through the line relay 84 of the first-selector F. It will also be seen that the trunk relay 77 is maintained energized through the line relay 95 by the second-selector H during the short interval that the first-selector F is permitted to remain in engagement with the trunk. The same is true of the second-selector H—that is, if either of the trunk conductors 184 or 185 is open as soon as the second-selector H seizes the trunk-line, then all of the switches—that is, the second-selector H, the first-selector F and the line switch C—will be released. Also, if the trunk-release conductor 186 is open, the second-selector H and the first-selector F will be released, because the release relays 97 and 86 cannot be maintained energized. These release relays, of course, while de-energized close a circuit between the release magnet and one of the line relay springs. For example, the release magnet 89 is connected with the line relay spring 135, and the release magnet 98 is connected with the line relay spring 164. Whenever the line relays 84 and 95 are de-energized, these springs 135 and 164 are, of course, connected to ground. It is for preventing a premature release

that the release relays are energized as soon as the line relays are energized, and this, of course, occurs at the instant that the switch is seized, as has been explained.

In connection with this system I elect to reserve one level of the second-selectors for other purposes than picking out connectors. In this case I will reserve the tenth level of the second-selectors, the trunk-lines leading therefrom terminating in apparatus shown in Fig. 6. This apparatus may be allotted to an operator for any purpose whatsoever. If a subscriber wishes to connect with an operator for any reason the second-selector is operated to raise the shaft wipers to the tenth level, and the second-selector then rotates on the tenth level and picks out an idle trunk such as the trunk the conductors 283, 284 and 285 of which terminate in the apparatus shown in Fig. 6. As soon as connection is established with the said trunk-line—that is, as soon as the selector side switch passes to third position, the line relay 286, similar to the line relay 95 of the second-selector H, energizes. The said relay then operates to press the springs 287, 288 and 289 into contact, the spring 287 being grounded. As soon as these springs come into contact the trunk-release conductor 285 is connected to ground G²¹ for the purpose of maintaining the release relays of the selector switches F and H energized. At the same time a signal lamp 290 is energized by a flow of current from ground G²¹ through the springs 287 and 288 to the lamp 290, thence through the springs 291 and 292 of the jack J to the battery lead 128, thence through battery B to ground G. The operator who is thereby given a signal answers by plugging into the jack J, separating the springs 291 and 292 and extinguishing the light 290. It will be seen that at any time the calling subscriber wishes to release he simply hangs up his receiver, as heretofore, thereby opening up the line circuit. As a result the line relay 286 (Fig. 6) de-energizes and permits the springs 287, 288 and 289 to separate, thereby removing ground from the trunk-release conductor 285, whereby the release of all the switches is initiated. The de-energizing of the said line relay also removes ground from the lamp 290, so that when the operator withdraws her plug the lamp 290 will not be lighted; or, in the event that the operator has already withdrawn her plug, the lamp 290 will go out.

From the foregoing it will be seen that I provide an improved two-wire automatic telephone exchange trunking system—that is to say, a system in which no operating grounds are employed at the substation, the two wires of the subscribers' lines being sufficient for controlling all of the operations at the exchange or central station, and

no third conductor being necessary outside of the said exchange or central station. This I accomplish without the necessity of providing special high resistance coils at the 5 substations, and without employing more than two trunk conductors leading to each first-selector. Trunks having third conductors are employed between the first-selectors and the second-selectors, and between the 10 second-selectors and the connectors; but any established connection from a calling substation is free from ground and of a two-wire character until it reaches the first-selector. Furthermore, the selectors and connectors are each provided with only one double-wound line relay, as distinguished 15 from the old arrangement which involved a pair of line relays for each selector and each connector. Again, it will be seen that I provide 20 subscribers' individual preliminary trunking switches that are each adapted to automatically restore itself if placed or left off normal when the subscriber's line is in normal condition—that is to say, when the 25 line is open or not in use. In addition, it will be seen that I provide a two-wire system in which provision is made for trunking to an operator's manual board for any desired purpose. No operating grounds or special 30 high resistance coils are employed at the subscribers' substations, and the battery current for talking purposes is supplied to the substations over the metallic or two-wire circuits provided therefor.

35 What I claim as my invention is:—

1. In a telephone system, a connector switch having a line relay and a slow-acting relay in series therewith for controlling all the connecting and releasing operations of 40 the said switch.
2. In an automatic switch, a line relay responsive to controlling impulses, a slow acting relay connected in series with said line relay but irresponsible to such impulses, operating means for said switch controlled 45

by said line relay, and restoring means for said switch controlled by said slow relay.

3. In an automatic switch, a line relay responsive to controlling impulses, a slow acting relay connected in series with said line relay but irresponsible to such impulses, and operating and restoring means for said switch each jointly controlled by said relays.

4. In a telephone system, a trunk line extending to a manual connective terminal, a signaling device associated with said terminal, means including an automatic switch controlled over the two sides of a calling line in series for extending a connection to said trunk line, a holding circuit including a non-talking conductor of said trunk line for retaining said switch in operated position, and a relay bridged across said trunk line in series with the exchange battery for controlling said holding circuit and said signaling device.

5. In a telephone system, an individual line switch of the type which is adapted to remain in operated position when operated, independent of the energization of any magnet, a selector adapted to be seized by said line switch, said selector being of the type which requires a substantially continuous closure of the line circuit to maintain it in operated position, a release magnet for said line switch, and means individual to said selector and responsive to a sustained opening of the line circuit for operating said release magnet.

6. In a telephone system, a trunk line, a subscriber's individual line switch for extending a connection to said trunk line, a release magnet for said line switch, a circuit for said magnet including an automatic interrupter, and means controlled over said trunk line for closing said circuit.

Signed by me at Chicago, Cook County, Illinois, this 25 day of January, 1908.

EDWARD A. MELLINGER.
